UNITED STATES PATENT OFFICE.

WILLIAM C. CULLITON, OF BUFFALO, NEW YORK.

DUMPING APPARATUS FOR UNLOADING RAILWAY-CARS.

SPECIFICATION forming part of Letters Patent No. 781,497, dated January 31, 1905.

Application filed March 17, 1904. Serial No. 198,689.

To all whom it may concern:

Be it known that I, WILLIAM C. CULLITON, a citizen of the United States, residing at Buffalo, in the county of Erie and State of New York, have invented certain new and useful Improvements in Dumping Apparatus for Unloading Railway-Cars, of which the following is a specification.

My invention relates more especially to improvements in a dumping apparatus for unloading railway-cars containing stone, coal, or other material; and it consists of the novel construction hereinafter described, and specifically pointed out in the claims.

The apparatus is designed to receive a transporting-car having one side removed—such, for instance, as are usually used at stone-crushing plants. When in use as a stone-transporting car and it is desired to dump the stone into the crusher, one side of the platform is raised to bring the same at an angle, and as the car is supported on and securely held to the platform it assumes the same angle as the platform and is held at such an angle until its entire contents has been dumped into the stone-crusher.

The object of the invention is to provide a tilting platform of simple construction which can be operated to dump a railway-car resting thereon by means of a pull-rod and which will be returned to its normal position automatically as soon as the contents of the car has been dumped and securely held in such position.

Other objects of the invention lie in the details of construction, which will be herein-after described.

Figure 1 represents a side elevation of the improved dumping apparatus in its normal position. In this view a car is shown positioned on the platform ready to be dumped. Fig. 2 is a similar view showing the platform in its inclined or dumping position, the car being shown on the platform. Fig. 3 is a top plan view showing the platform in its normal position without the car. Fig. 4 is a vertical section taken on line 4-4, Fig. 1, the platform being shown in its normal position. Fig. 5 is a similar view with the platform shown in its inclined or dumping position.

Fig. 6 is an enlarged fragmentary longitudinal section of the longitudinal pivot-timber, taken through one of the metal-faced trunnions. Fig. 7 is a transverse section taken on line 7-7, Fig. 6. Fig. 8 is an enlarged vertical section taken on line 8-8, Fig. 5.

A represents the platform, which carries a section of the track A', the said platform being supported by a foundation B, some of the cross-beams of which are inclined to one side from the pivotal point of the platform, as at C, in order to form a stop or support for the said platform when the same is in its inclined or dumping position. The platform is pivotally connected with the foundation B by means of a longitudinal pivot-timber D, arranged underneath the platform at a point somewhat nearer to the side opposite to that from which the car is dumped. This pivot-timber is provided with journals or trunnions D', which are located near opposite ends of the platform and revolve in bearings E, secured to two cross-beams. The trunnions are formed by reducing the pivot-timber at two points and inclosing the said reduced portions in metal casings F, each having a cylindrical outer face and being formed in two half-sections e e, bolted together by means of bolts e' e', as clearly shown in Figs. 6 and 7.

The platform is usually formed of a series of ties G, to which the rails H and I, forming a portion of the track A', are secured in any well-known manner. The rail I, which is located on that side of the platform adapted to be elevated when dumping the latter, is made somewhat longer than the rail H, so that a considerable portion of the weight of the car moved onto the platform will be supported by the foundation B. This arrangement also prevents depression of the platform when the car rides upon the same, the ends of the portion of the rail I on the platform being supported on the foundation B, thus having the same solid support given the adjacent portions of said rail. The rail H is, by preference, provided with a raised outer portion forming a ledge h, which prevents displacement of the car when the platform is inclined by reason of the outer faces of the

wheels on the dumping side resting against the said ledge. A metal plate J is arranged parallel with the rail I, secured to the platform, and projects upwardly therefrom. This plate is provided upon its upper edge with an outwardly-extending flange j , and to the under side of the car, opposite to the dumping side, is also attached a plate K, provided with a groove k . The flange of the plate J is adapted to engage the groove k in the plate K when the car is on the platform, thereby, with the aid of the ledge h on the rail H, securely holding the car on the platform when the same is in its inclined or dumping position.

To one of the beams of the foundation B are pivotally attached two dogs L L, which are confined in guide-straps N N, also attached to one of the foundation-beams. The upper ends of the dogs engage two of the cross-ties G G of the platform, thereby securely fastening the platform against movement on the foundation. The dogs are released from contact with the platform by means of a bar O, which is pivotally attached to the said dogs L L and is provided with an eye o at each end thereof, the eye at one end being engaged by one end of a pull-rod S and the eye at the other end having one end of a retractile spring Q attached thereto, the other end of the said spring being secured to one of the vertical beams of the foundation, as at R, the said spring serving to control the operation of the bar O.

The center cross-tie T of the dumping-platform is provided at the elevating side of the latter with an eye t , and to this eye is attached one end of a rope U, that passes down over a pulley V and is wound around a drum V', the outer end of the rope being attached to a weight W. The pulley V and drum V' are journaled in a frame X, arranged at the side of the platform opposite the dumping side, as shown in Figs. 4 and 5.

To operate the dumping-platform, a loaded car is run upon the same, during which action the plate J engages the plate K. The pull-rod S is then drawn in the direction of the dart z , Fig. 1, causing the bar O to release the dogs L L from engagement with the platform and permitting the same to tilt or incline in order to discharge the contents of the car by reason of the platform being pivoted out of the medial line and also by reason of the weight of the car overcoming the weight W. After the car has been emptied it and the platform are automatically returned to their normal position by means of the weight W, this weight being sufficiently heavy to overcome the weight of the empty car and platform, at which times the dogs L L automatically engage the platform and fasten the same in position.

In Figs. 4, 5, and 8 I have shown a friction band-brake consisting of a friction-disk Y, secured to the rope-drum V', a friction-

belt Z passing around the friction-disk and in contact therewith, the ends of the belt being fastened to pins $z' z'$, projecting from the face of a bell-crank lever Z', that is secured to a crank-shaft Z'', loosely journaled in the frame beneath the rope-drum. This brake is intended to be brought into action in case the platform is returned too rapidly to its normal position, which is likely to occur in many instances where the platform has received a light-built car designed to receive a lighter grade of stone or other material.

Having thus described my invention, what I claim, and desire to secure by Letters Patent, is—

1. In a car-dumping apparatus, the combination of a foundation, and a dumping-platform pivotally secured to said foundation and having a pivot-timber arranged lengthwise underneath the same, said pivot-timber being provided with reduced portions and having separable metal casings surrounding said reduced portions.

2. In a car-dumping apparatus, the combination of a foundation, and a dumping-platform carrying a section of a track, one rail of said track extending beyond the end of said platform and bearing against the foundation.

3. In a car-dumping apparatus, the combination of a foundation, and a dumping-platform carrying a section of a track, one rail of said track extending beyond the ends of the platform and receiving support on the foundation.

4. In a car-dumping apparatus, the combination of a suitable foundation, a dumping-platform secured to said foundation and carrying a car having a longitudinally-grooved plate secured to its under side, and a flanged plate secured to said platform and being adapted for engagement with the grooved plate on the car.

5. In a car-dumping apparatus, the combination of a dumping-platform, trunnions attached thereto, a foundation provided with keepers adapted to be engaged by the trunnions, a stop on the foundation consisting of an inclined surface, a flanged plate adapted to secure a car to the platform, two pivoted dogs, a spring-controlled bar pivotally attached to the dogs, and means for operating the bar, substantially as described.

6. In a car-dumping apparatus, the combination of a foundation, a dumping-platform pivotally secured to the foundation and having a series of cross-ties, suitable dogs pivotally secured to the foundation, each being adapted for engagement with one of said cross-ties, a rod connecting said dogs, and a retractile spring secured at one end to the foundation and at its other end to the said rod.

7. In a car-dumping apparatus, the combination of a foundation, a platform pivotally secured to said foundation, fastenings to retain the platform in its normal position, means

for actuating said fastenings, and means for automatically returning the platform to its normal position comprising a rope attached at one end to the platform, a drum around which said rope is wound, and a weight attached to the other end of said rope.

8. In a car-dumping apparatus, the combination of a pivoted platform supporting a car, a foundation for the platform, metal plates attached to the platform and car, fastenings to retain the platform in its normal position, means for operating the fastenings, means for automatically returning the platform to its

normal position, comprising a rope attached at one end to the platform, a pulley, a drum around which the rope is wound, and a weight attached at the other end of the rope, all substantially as described.

In witness whereof I have affixed my signature in the presence of two subscribing witnesses.

WILLIAM C. CULLITON.
